CLAIM

The ornamental design for a hand stamp handle top, as shown and described.

DESCRIPTION

FIG. 1 is a perspective view of a hand stamp handle top showing my new design;

FIG. 2 is a top plan view thereof;

FIG. 3 is a side elevational view thereof, all sides being identical to the side shown;

FIG. 4 is a top plan view of a first embodiment of FIG. 1;

FIG. 5 is a side elevational view thereof, all sides being identical to the side shown;

FIG. 6 is a top plan view of a second embodiment of FIG. 1; and,

FIG. 7 is a side elevational view thereof, all sides being identical to the side shown.

The broken line showings of a stamp housing and stamp handle body portions in FIG. 1, and of stamp handle body portions in FIG. 3, FIG. 5 and FIG. 7 are for illustrative purposes only and form no part of my design.

The T-like symbol shown in broken lines in FIG. 1, FIG. 2, FIG. 4 and FIG. 6 is for illustrative purposes only and forms no part of the claimed design.
